(57) **CLAIM**

The ornamental design for a laser engraving machine, as shown and described.

DESCRIPTION

FIG. 1 is a front view of a laser engraving machine showing our new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a front left perspective view thereof; and,

FIG. 8 is a rear right perspective view thereof.

The broken lines immediately adjacent to the shaded areas depict the bounds of the claimed design, while all other broken lines are directed to environment. The broken lines form no part of the claimed design.

1 Claim, 8 Drawing Sheets
